UNITED STATES PATENT OFFICE.

JAMES J. TURNER, OF RICHMOND, INDIANA, ASSIGNOR TO HIMSELF AND
JOHN F. MILLER, OF SAME PLACE.

SWITCH AND SIGNAL INTERLOCKING.

SPECIFICATION forming part of Letters Patent No. 381,093, dated April 10, 1888.

Application filed March 3, 1887. Serial No. 229,492. (No model.)

To all whom it may concern:

Be it known that I, JAMES J. TURNER, of Richmond, county of Wayne, and State of Indiana, have invented a new and useful Improvement in Switch and Signal Interlocking, of which the following is a true and exact description, due reference being had to the accompanying drawings, which form a part of this specification.

10 My improvement relates to the well-known class of devices by which railway switches, signals, and switch-locks are so interlocked as to prevent a safety-signal being given except when the route governed by it is clear and all conflicting signals locked to "danger."

15 The object of my invention is to provide improved devices for interlocking the actuating-levers by means of their latches.

20 My invention consists, first, of a novel combination of the lever-latches with movable segments and a rotating shaft connected with the interlocking frame, whereby the shaft is partially rotated by the disengaging of the latch and its full movement completed by the 25 engagement of the latch after the lever has been thrown; second, in the combination of the rotating shafts actuated by the lever latches with rotating shafts crossing but not intersecting the same and actuated by them 30 through spiral gear-wheels; third, in the combination of the shafts actuated by the latches and the shafts crossing and actuated by the said 35 shafts, with rotating locking-dogs arranged in pairs where the shafts cross each other and so placed that the switch, switch-lock, and signal-actuating levers can only be unlatched and moved in a proper regulated sequence; fourth, in a special locking device whereby the movement of one lever is made absolutely dependent upon the relative movement of two other 40 levers—as, for instance, the movement of a signal-lever being made dependent upon the relative movement of two switch-levers; lastly, in improved devices and combinations of devices hereinafter described, and by means of which my improved interlocking system is 45 perfected and adapted for use.

Reference being now had to the drawings which illustrate my invention, Figure 1 is a 50 perspective view of one end of the levers and interlocking frames embodying my invention.

Fig. 2 is a side view of one lever, showing its connection with a rotating shaft and with the interlocking frame. Figs. 3, 4, and 5 show the various positions of the crank-arms on the 55 rotating shaft actuated by the lever during the operation of unlatching, moving the lever, and again latching it. Fig. 6 is a perspective view of one of my levers with its connected latch, segment, and shaft, showing also a portion of the interlocking frame. Fig. 7 is a 60 view of a pair of my improved rotating locking-dogs. Figs. 8, 9, and 10 are perspective views of my improved rotating locking-dogs, illustrating the manner in which they mutually 65 lock and release each other and their connected shafts. Figs. 11, 12, 13, 14, and 15 are views of my improved device for causing the motion of one shaft to depend on the relative movement of two other shafts, showing, respectively, the different positions taken by the lock during the movement of the two governing-shafts. Fig. 16 shows the above device from a point at right angles to that of the views in Figs. 12 to 15. Fig. 17 is a plan of 70 intersecting tracks, showing the various elements to be interlocked and my plan of accomplishing such interlocking; and Fig. 18 is a view of my interlocking frame, showing the various shafts as interlocked in the positions 75 they would occupy in the condition of the system indicated in Fig. 17.

A is the frame in which the levers are secured, the levers being pivoted at a.

A' is an arched segment secured to frame A 85 and provided with detents a' for the lever-latches.

A² is a hanger having a slot, a², which serves as a guide for the movable segment which actuates the shaft.

B, B, &c., are the levers, which have slots b in them to guide the latches b'.

B' is the latch-handle; b', a continuation of the latch, also guided in the slot b, and to which is attached the pin b'.

B² is a T-head on the lever B, and B³ and B⁴ rods actuating switches, &c.

C is a curved segment having a slot, C', in which fits and moves the pin b'.

C² is a guide-pin attached to the center of C 100 and adapted to rest in the slot a² of the hanger A².

C³ are slotted lifting-blocks pivoted at each end of the segments C upon pivots c.

C⁴ are slots adapted to receive the crank-arms of the rotating shaft D, which has bearing in the frame A, said crank-arms D' D² being arranged at an angle of about forty-five degrees to each other.

d is a locking-plate secured on shaft D between its crank-arms D' D², its function being to prevent the shaft rotating during the throw of the lever B.

E E' are spiral gear-wheels secured, respectively, to the shafts D and the cross-shafts G, and by means of which the shafts G are caused to revolve.

F F' are my improved rotating locking-dogs, arranged, respectively, on the shafts D and cross-shafts G in pairs so placed as to produce the required interlocking between them.

G are cross shafts held in an interlocking frame, and, as before stated, actuated by the shafts D, and interlocked with them by means of the dogs F F'.

H H' are eccentrics secured on the shafts D; I I', eccentric rings and levers actuating the forked lever J.

K is a collar sliding freely on a shaft and actuated through lever J, and having a guide-pin, k, and slot k', adapted to engage with a feather, L, secured to the shaft on which it slides.

N is a guide in which the pin k rests and slides, and M a special device which is shown as an element of the system indicated in Figs. 17 and 18, but which is not my invention and need not therefore be particularly described.

The operation of my interlocking system may readily be followed on the drawings. In Figs. 1 and 6 the levers B are shown as in the same position and latched. When it is desired to move an element actuated by one of these levers, the latch b' is drawn up out of the detent a', and this upward movement of the latch also raises the segment C by means of the pin b³ to the position shown in Fig. 2. The slotted lifting-block c³ nearest to the pin b³ is of course raised with the upward movement of the segment C, and by its movement a partial turn is given to the shaft D by means of the crank-arm D².

This turn of the shaft D throws the crank D' from the position shown in Fig. 3 to that shown in Fig. 4, and turns the locking-plate d into the vertical plane, as shown in Fig. 2. The lever B is now thrown back, its side resting against or close to the locking-plate d during the whole of the throw, and the shaft D being therefore securely locked in the angular position brought about by the lifting of the latch. When the throw of the lever is

completed, the latch is allowed to fall into the detent a' on the other side of the arched segment A' and the pin b³ presses down the back end of the segment C and the lifting-block attached to it, which, acting on the crank-arm D', causes the shaft D to complete its revolving motion, the crank-arms being brought

to the position shown in Fig. 5. The return movement of the lever is made in the same way, and the shaft D thereby returned to its initial position.

It is unnecessary to describe the connection of the levers B with the various elements of the route governed by them, as any approved plan may be used, and this forms no part of my present invention.

The shafts D are prolonged into the interlocking frame, in which also are secured rotating shafts G, crossing and lying in a plane parallel to the plane of the shafts D.

Upon each of the shafts G is secured a spiral gear-wheel, E', which engages with a similar gear, E, attached to one of the shafts D. The number of shafts G will vary with the combinations and number of conflicting elements in the interlocked routes.

Upon each shaft D as it traverses the interlocking frame are secured locking-dogs F, which engage with locking-dogs F', secured upon shafts G, which are actuated by levers which should be moved in a certain relative order with the lever actuating such shaft D.

As will at once be seen, the shafts D, which are connected with shafts G by means of the spiral gears E E', give to such shafts a movement of rotation coincident with their own, and the angular movement of the locking-dogs secured on the crossing shafts being fixed and known, their angular position on the shafts and their relative size and clearance can be determined in each case, so that they may engage and disengage according to the determined order of movement of the actuating-levers. The construction and arrangement of these locking-dogs are clearly shown in Figs. 7, 8, 9, and 10. In Fig. 8 the dog F' is locked by the dog F. In Fig. 9 the dogs are disengaged and either shaft may be revolved, while in Fig. 10 the dog F is locked by the dog F', these three figures showing, substantially, the combinations of which any one pair of locking-dogs are capable.

In Fig. 18 may be seen a complete interlocking system adapted to the conditions shown in the plan Fig. 17, in which O O', &c., represent signal connections, P P', &c., switch-connections, and R R', &c., switch-lock connections, and one skilled in the art can readily follow the interlocking, as shown in Fig. 18, or modify it to suit the conditions of any particular case.

I have found it desirable in some cases to actuate two signals with one lever, making the signal thrown depend upon the position of one of the switches governed by such signals—as, for instance, lever 2 actuates signals 2^a and 2^b in Fig. 17, according to the position of the switch 4^a. By an invention which, as it is also applicable to other systems of interlocking, I have made the subject of a separate application for Letters Patent I cause the throwing of the lever-actuating switches 4^a and 4^b, Fig. 17, to effect a change in the signal-connection

actuated by the lever 2. Thus, when switches 4^a and 4^b are set for the main line, lever 2 would actuate signal 2^a, and when said switches are set for the siding or throw-off the same lever 5 would actuate signal 2^b. It is evident that in such a case where a single lever is alternately connected with signals governing different routes the system of locking-dogs heretofore described could not be so arranged as to insure 10 that the route was properly set before the signal "safety" was given. To provide for such cases I have devised the arrangement shown in Figs. 11 to 16, Fig. 11 showing the position of 4 D and 6 D, the shafts actuated by levers 15 4 and 6, Fig. 17, corresponding with the arrangement of track shown in said figure, lever 4 having set-switches 4^a and 4^b for the main line and lever 6 having set-switches 6^a and 6^b for the siding or throw-off. It is safe to throw 20 lever 2 to actuate signal 2^a, the actuating-lever of which has its shaft 2 D, Fig. 18, connected by gears E E' with the cross-shaft 2' G.

The results of closing the line shown open in Fig. 17 and of opening the line shown there 25 as closed can be readily followed in Figs. 11 to 15. The signal 2^a being set to "danger," the feather L on the shaft 2' G is in line with slot k' in sleeve K. The unlatching of lever 4 to set switch 4^a for the siding rotates the 30 shaft 4 D to the position shown in Fig. 12, and the eccentric H draws the sleeve K over the end of feather L by means of the strap and rod I and forked lever J. The result of relatching this lever is shown in Fig. 13. Unlatching lever 6 to set switches 6^a and 6^b for the 35 main line moves the collar K back, as shown in Fig. 14, and the relatching of this lever in the position which sets the switches 6^a and 6^b for the main line moves the collar K back to a position which disengages it from feather L 40 and leaves lever 2 free again to move and actuate signal 2^b.

I have now described my improvements as 45 shown in the drawings and in what I believe to be their best and most efficient form. It will at once be seen, however, that in many details the device as shown can be modified or changed without departure from the invention or substantial difference in the mode of 50 operation. Thus, instead of the straight and curved slots shown as guides and bearings, any desired form of guide or bearing may be substituted. The slotted blocks C³ need not necessarily be pivoted on the ends of the segment C, but can be rigidly secured thereto, or they may, of course, be replaced by a swinging link or pitman hinged on the segment C and to the crank-arms of shaft D. Other similar uses of one well known mechanical equivalent 55 for another might be pointed out; but it is unnecessary to do so, as what I have said will indicate that my claims are not intended to be confined to the precise arrangement of the parts as shown, save where this is distinctly 60 expressed in such claims.

Having now described my invention, what I

claim as new, and desire to secure by Letters Patent, is—

1. In a switch and signal interlocking device, the combination of the latch of the actuating-lever with a movable segment, C, connected with and operated by said latch and having crank-operating devices at each end, and a rotating shaft having crank arms formed in it at an angle of about forty-five degrees 70 with each other, said shaft connecting with an interlocking frame.

2. In a switch and signal interlocking device, the combination of the actuating-levers secured in a frame, latches secured to said levers, movable segments C, connected with and operated by said latches and having crank-actuating devices at each end, rotating shafts having crank-arms formed therein at an angle of about forty-five degrees to each other, and 80 a locking-plate, d, secured upon the shaft between the crank-arms, as shown and described, so that the shaft, having made half its revolution during the unlatching of the lever, is locked against the lever until it has completed 85 its throw and is in position to be latched again.

3. In a switch and signal interlocking device, the combination, in a frame, of the actuating-lever having a latch secured to and actuating a movable segment, C, and through it a 95 rotating shaft having crank-arms, all substantially as specified, and the detent-segment A', having detents a' a', corresponding to the two normal positions of the actuating-lever, said segment being of circular outline between the 100 detents, so as to hold the latch stationary during the throw of the lever.

4. In a switch and signal interlocking device, the combination, in a frame, of the slotted actuating-lever having a latch-extension 105 moving in said slot and connected with a slotted segment, C, having crank-actuating devices attached to each end, and the shaft D, having crank-arms, substantially as shown and described, said segment being guided in a vertical direction by a slotted hanger, A².

5. In a switch and signal interlocking device, the combination, with rotating shafts in the interlocking frame connected with and actuated by the latches of the actuating-levers, 115 of rotating shafts actuated by the shafts connected with the lever-latches by spiral gear-wheels, said two systems of shafting crossing but not intersecting each other in parallel planes, so that locking devices can be secured 120 to the shafts in such manner as to interlock any shaft with any other shaft or lever and in any desired sequence.

6. In a switch and signal interlocking device, the combination of the movable segments 125 C, connected with and actuated by the lever-latches, the shafts D, having crank-arms D' D', said shafts extending across the interlocking frame, and a system of shafts crossing but not intersecting the shafts D in said interlocking 130 frame, said shafts being connected with and actuated by shafts D.

7. In a switch and signal interlocking device, the combination of shafts D, connected with and actuated by the latches of the actuating-levers, the transverse system of shafts G 5 G, &c., connected with and actuated by the shafts D through spiral gears E E', and the rotating locking-dogs F F', secured to the upper and lower system of shafts in pairs at their points of intersection.
- 10 8. In a switch and signal interlocking device, the combination of a system of rotating shafts connected with and operated by the latches of the actuating-levers, a system of rotating shafts crossing but not intersecting the 15 first shaft system and actuated by it, substan-

tially as described, and the device for making the movement of any lever dependent on the relative position of two other levers, which consists of the cams H H', secured to two shafts connected with the two levers whose relative 20 position is to govern the third lever, the feather L, secured in a cross-shaft connected with the third lever, the cam-rings and connecting-rods I I', the lever J, and the slotted sleeve K, all connected and operating substantially as shown 25 and described.

JAMES J. TURNER.
